UNITED STATES PATENT OFFICE

CURT O. HESSE, OF BROOKLYN, NEW YORK, ASSIGNOR TO H. B. WIGGIN'S SONS COMPANY, OF BLOOMFIELD, NEW JERSEY, A CORPORATION OF NEW JERSEY

DESIGN FOR A WALL PAPER OR SIMILAR ARTICLE

Application filed October 11, 1930. Serial No. 37,234. Term of patent 3½ years.

To all whom it may concern:

Be it known that I, CURT O. HESSE, a citizen of Germany, residing at Brooklyn, in the county of Kings and State of New York, have invented a new, original, and ornamental Design for Wall Paper or Similar Article, of which the following is a specification, reference being had to the accompanying drawing, forming a part thereof.

The figure is a front face view of one unit of a recurring pattern which occurs at regular intervals on the wall paper or similar article of my new design, the unit being repeated vertically on the lines B—B and repeated horizontally on the lines A—A, each unit on the right or left being raised or lowered one-half of the vertical distance of the unit.

I claim:

The ornamental design for a wall paper or similar article, as shown and described.

CURT O. HESSE.
